UNITED STATES PATENT OFFICE

109,809

DESIGN FOR A DECORATIVE NAIL

Joseph Jacobs, Brooklyn, N. Y.

Application April 20, 1938, Serial No. 76,633

Term of patent 3½ years

To all whom it may concern:

Be it known that I, Joseph Jacobs, a citizen of the United States and a resident of the city of New York, in the county of Kings, Borough of Brooklyn, and State of New York, have invented a new, original, and ornamental Design for Decorative Nails, of which the following is a specification; reference being had to the accompanying drawing, forming part thereof.

Fig. 1 is a top view of a decorative nail embodying my new design.

Fig. 2 is a front elevation thereof.

I claim:

The ornamental design for a decorative nail, as shown.

JOSEPH JACOBS.
